UNITED STATES PATENT OFFICE.

HERMANN LEMP, OF ERIE, PENNSYLVANIA, ASSIGNEE TO GENERAL ELECTRIC COMPANY, A CORPORATION OF NEW YORK.

SAFETY DEVICE FOR INTERNAL-COMBUSTION ENGINES.

1,080,765.

Specification of Letters Patent.

Patented Dec. 9, 1913.

Application filed December 30, 1912. Serial No. 739,205.

To all whom it may concern:

Be it known that I, HERMANN LEMP, a citizen of the United States, residing at Erie, in the county of Erie, State of Pennsylvania, have invented certain new and useful Improvements in Safety Devices for Internal-Combustion Engines, of which the following is a specification.

From time to time serious accidents occur in power plants having high compression engines operating on the constant pressure plan. The accidents, often resulting in the loss of life or limbs, are caused by the bursting of the air tanks or blast bottles as they are commonly called. These bottles, which supply the necessary air to inject the fuel, are under very high pressure, 900 to 1000 pounds per square inch not being uncommon. Various theories as to the cause of these accidents have been advanced but no complete remedy has heretofore been devised to my knowledge. Careful analysis shows that the real cause is due to the more or less gradual accumulation of vapors of fuel or lubricating oil in the air blast bottles and in the pipes leading therefrom to the engine pulverizers until a highly combustible mixture is formed which is ignited by a rise in temperature due to a flame or hot charge blowing back from the engine cylinder through the fuel admitting valve of the pulverizer. To give an approximate idea of the situation under the conditions specified, the pressure in one of these bottles would probably be from two and one-half to three times the normal air pressure, and the bottle would burst unless the factor of safety was very much higher than is normally necessary. These accidents are comparatively rare, a fact which renders necessary some form of safety device which does not become inoperative from lack of attention or use.

The object of my invention is to provide a safety device which will fulfil the conditions referred to above.

In the accompanying drawing, which illustrates one of the embodiments of my invention, Figure 1 is a partial view of an internal combustion engine equipped with my improved safety device; Fig. 2 is a view in side elevation of the safety device; and Fig. 3 is a sectional view thereof.

4 indicates the cylinder of an internal combustion engine operating on the constant

pressure plan. That is to say, an engine in which air is compressed to a temperature above the igniting temperature of the fuel, which fuel is injected through a pulverizer or atomizer into the combustion space by a 60 blast of air under high pressure.

5 indicates a fuel pulverizer of any suitable or well known construction. Fuel is admitted thereto by the pipe 6 and high pressure compressed air from the blast bottle 7 by the pipe 8. The admission of fuel to the engine is controlled by the needle valve 9 which is actuated by the lever 10 from the cam shaft. The passage of air from the blast bottle is controlled by the 65 hand valve 11. In the pipe 8 between the blast bottle and fuel pulverizer is situated my improved safety device 12. This device should be mounted close to the engine and preferably on the pulverizer itself. The 70 safety device comprises a casing 13 having a screw threaded nipple for mounting it on the pulverizer, and a second screw threaded nipple to receive the coupling of pipe 8. In the casing is a passage 14 which may extend diagonally with respect to the axis of the needle valve so that in the event of back 75 firing in the engine as little resistance as possible will be offered to the passage of the gases, as in Fig. 1, or it may extend perpendicular to the axis of the pulverizer as in 80 Fig. 2.

The passage 14 terminates in a chamber 15, one wall of which is formed by a thin metallic diaphragm 16. The diaphragm is 85 held in place by a nut 17 that is screw threaded to the casing. The nut is provided with a central opening 18 of relatively large area. The diaphragm can with advantage be made of thin copper and in ordinary 90 service should be capable of withstanding a pressure of from 2000 to 2500 pounds per square inch. This pressure will be determined by the blast pressure and by the pressure in the combustion chamber of the 95 engine.

Located at one side of the passage 14 is a second passage 19 that communicates with the pipe 8 leading to the starting bottle. The mouth of this passage is shaped to form a conical seat for the ball valve 20. This valve is free to open when air flows from the bottle to the engine, but closes and prevents the passage of fluid from the engine to the bottle. The valve and its seat are so ar- 100 105 110

ranged with respect to the diaphragm that the latter acts as a means to prevent the valve from getting out of place.

It will be noted that the passages 14 and 5 19 are parallel for a portion of their length. This serves as an additional means to prevent the passage of gases from the engine to the bottle for the reason that when back firing occurs the gases strike the diaphragm 10 16 and disrupt it, there being comparatively little tendency of the gases to turn and flow through the passage 19 in the opposite direction. In any event the ball valve would close and prevent this action from taking 15 place. This offset arrangement of the passages is important for the reason that it offers a material resistance to the flow of gases into the passage 19 when the engine back fires toward the bottle, even though 20 the ball valve should, for any reason, fail to completely close.

A diaphragm arranged as shown will not fail to operate under abnormal pressure conditions and does not require to be tested 25 from time to time to see if it is in good condition. Any deterioration of the material would merely mean that the diaphragm would blow out at a little lower pressure than was originally intended. This would 30 not be harmful.

By making the diaphragm out of copper, or some similar material, it will be torn or split when disrupted, as distinguished from bodily separating the central part of the 35 diaphragm from that under the retaining nut. Due to this fact the operator is not endangered even though he is standing in line with the diaphragm at the time. In practice the safety device should be so positioned that the diaphragm is pointed away 40 from any place that the operator is required to stand in the performance of his duties. Preferably the diaphragm is pointed upwardly.

In accordance with the provisions of the 45 patent statutes, I have described the principle of operation of my invention, together with the apparatus which I now consider to represent the best embodiment thereof; but I desire to have it understood 50 that the apparatus shown is only illustrative and that the invention can be carried out by other means.

What I claim as new and desire to secure by Letters Patent of the United States, is,— 55

1. An internal combustion engine having a fuel pulverizer, and a blast bottle connected thereto for introducing fuel into the engine cylinder in combination with a safety device interposed between the pulverizer 60 and bottle which comprises a casing, a thin metallic diaphragm which is normally exposed to the pressure in the blast bottle and under abnormal conditions to the pressure in the cylinder, and a check valve which is 65 opened by the fluid flowing from the bottle to the engine and is closed by fluid tending to flow in the opposite direction.

2. An internal combustion engine having a fuel pulverizer and a blast bottle connected thereto, in combination with a safety device comprising a casing containing a chamber, a passage leading therefrom to the pulverizer, a thin metallic diaphragm forming one wall of the chamber, a second passage communicating with the chamber and the blast bottle, said passages being offset to prevent direct flow of fluid from one to the other, and a check valve which is located in the second passage between the chamber and 75 the bottle.

In witness whereof, I have hereunto set my hand this 26th day of December, 1912.

HERMANN LEMP.
